(57) **CLAIM**

The ornamental design for a guitar body, as shown and described.

DESCRIPTION

FIG. 1 is a front perspective view of the guitar body.

FIG. 2 is a front elevational view of the guitar body.

FIG. 3 is a rear elevational view of the guitar body.

FIG. 4 is a left side view of the guitar body.

FIG. 5 is a right side view of the guitar body.

FIG. 6 is a top view of the guitar body; and,

FIG. 7 is a bottom view of the guitar body.

The shading is provided to illustrate contour only and is not an indication of texture, gloss, etc. The broken lines illustrate the portions of the guitar body that form no part of the claimed design.

1 Claim, 6 Drawing Sheets
